UNITED STATES PATENT OFFICE.

EMILE MARTIN, OF NEW YORK, N. Y.

METHOD FOR PRODUCING PERMANENT WAVES IN THE HAIR.

Application filed July 14, 1922. Serial No. 575,084.

To all whom it may concern:

Be it known that I, EMILE MARTIN, a citizen of the United States, residing at New York, in the county and State of New York, have invented a certain new and Improved Method for Producing Permanent Waves in Hair, of which the following is a specification.

My invention relates to methods of producing waves in hair, and more especially to those methods which produce what are ordinarily known as permanent waves, as will be more fully hereinafter described.

Referring to the drawings: Figures 1, 2, 15 3 and 4 show various steps in my method, and Figure 5 shows an end view of a completely assembled structure, looking at Figure 4 from the right.

Referring to the specifications: Figure 1 20 shows a stick which can be of any cross sectional form—round, square, rectangular, oval, or otherwise, as may be desired, although I prefer to use ordinarily a round stick. This stick can be made of any suitable material, but I prefer to use aluminum.

Upon the stick is wound spirally the strand of hair 2, which has previously been twisted. The strand of hair is secured to the stick by tying it at each end as shown, 30 or throughout its length, with a string or tape 3, or in any other suitable manner that will secure it in position upon the stick 1.

Over the outside of the strand of hair 2 I place a layer of flannel 4, or other similar 35 material, by wrapping it thereon tightly, and upon this layer I tightly wind a second layer of flannel 5, or similar material—Figure 3. These two layers or coverings of flannel I moisten or saturate with solutions, 40 as will be more fully hereinafter described.

Upon the outer covering of flannel 5 I slip a paper tube 13, and upon the outside of this tube I slip an electric heater or unit 6, of tubular form, preferably open at both ends. 45 This heater comprises a casing 9, in which is suitably mounted an electric resistance 7, designed to give the desired heat upon being connected to a source of electrical energy. This resistance 7 is separated from the casing 9 by any suitable insulation 8, which will withstand the heat to which the device is subject in operation.

At one end of the heater 6 I provide terminal connections 10 and 11, through which 50 the wires 12 pass to the source of electric supply.

In carrying out my invention, the first layer of flannel 4, Figure 2, I moisten or saturate with and wring out in an aqueous alkaline solution, which I may make up according to one of the following formulæ:

16 parts borax 1 part bicarbonate or borate of soda 40 parts water or 1 part bicarbonate of potash 5 parts water. These solutions I may perfume, if desired. I also may change the proportion of these ingredients, or use other combinations of the same or other alkaline materials.

The second layer of flannel 5, Figure 3, I moisten or saturate with and wring out of one or more vegetable oils. I find good results can be obtained with equal parts of linseed oil and olive oil.

The method of producing a permanent wave by my new method will now be readily understood as follows:

First step: The hair is thoroughly washed to remove all dirt or other extraneous matter.

Second step: The hair is sprayed with an alkaline solution.

Third step: The hair is wound upon the stick.

Fourth step: The hair is again sprayed with an alkaline solution.

Fifth step: The hair is covered with a strip of flannel moistened or saturated with an alkaline solution.

Sixth step: A second strip of flannel, moistened or saturated with vegetable oils, is then placed over the first covering of flannel.

Seventh step: A paper tube is slipped over the outside of the outer flannel covering.

Eighth step: A tubular heater is placed over the outside of the paper tube. This heater is preferably electrically heated.

In about five minutes after the current is turned on the water in the alkaline solution is evaporated from the hair and the first layer of flannel, and this permits the vegetable oils in the second layer of flannel to permeate the hair, causing the hair to assume a permanent wave.

The operation is completed in about ten minutes application of the heat, after which the heater 6, paper tube 13 and flannel coverings 4 and 5 are removed, and the stick 1 is withdrawn.

I have found from experience that the best results are obtained when the heater is cold.

when put on. I have also found that where an alkaline solution is used alone it makes the hair brittle, and after it has been once waved by such a process, it is liable to break 5 upon receiving a second treatment. I have entirely overcome this objection, and other disadvantages in the old methods, by using vegetable oils and carrying out my method as described above. In my method the hair 10 remains soft and pliable and does not become brittle and break.

It is obvious to anyone skilled in the art to which this invention belongs that various modifications of my method can be made 15 without going outside of my invention.

I do not limit my method in any way to the use of any particular form of device such as shown in the drawing, as many forms of apparatus can be used to carry out 20 my invention.

Having described my invention, what I claim and wish secured by Letters Patent is:

1. The herein described method of waving hair which consists in coiling the hair in the 25 desired form, subjecting the hair first to the action of an alkali, second to the action of vegetable oils and third to the application of heat.

2. The herein described method of waving 30 hair which consists in moistening the hair with an alkaline solution, placing over the hair a covering, also moistened with an alkaline solution, placing a second covering, moistened with vegetable oils, over the first 35 named covering, and then applying a temperature sufficient to evaporate the water of the alkaline solution and allow the oils to permeate the hair.

3. The herein described method of waving 40 hair, which consists in coiling the hair in spiral form, spraying the hair with an alka-

line solution, binding the hair with a covering saturated with an alkaline solution, applying a second covering saturated with vegetable oils, and finally applying a temperature to a degree sufficient to evaporate the water of the alkaline solution. 45

4. The herein described successive steps in waving hair, which consists in coiling the hair in the desired form, subjecting the hair first to an aqueous solution containing borax and bicarbonate of soda, and second to the action of a mixture of linseed and olive oils. 50

5. The herein described method of waving hair, which consists in coiling the hair in the desired form, subjecting the hair first to the action of an alkaline solution, second to the action of vegetable oils, and third to the application of heat and mechanical pressure. 55 60

6. The method of waving hair consisting in giving the hair the desired form, then treating the hair with an alkaline solution and with vegetable oils, and finally heating it. 65

7. The method of waving hair consisting in giving the hair the desired form, then treating the hair with an aqueous solution of bicarbonate of potash and with a vegetable oil, and finally heating it. 70

8. The method of waving hair consisting in giving the hair the desired form, then treating the hair with an aqueous solution of borate of soda and with a vegetable oil, and finally heating it. 75

In testimony whereof, I affix my signature, in the presence of two witnesses.

EMILE MARTIN.

Witnesses:

HENRY PRICE BALL,
CICILE JEAN STRAUSS.
